US00D440164S

(12) **United States Design Patent**
Kerr

(10) Patent No.: US D440,164 S
(45) Date of Patent: ** Apr. 10, 2001

(54) MEASURING CUPS

3,526,138 * 9/1970 Swett et al. 73/426

(75) Inventor: **Helen Kerr**, Toronto (CA)

* cited by examiner

(73) Assignee: **Browne & Co. Ltd. (CA)**

Primary Examiner—Terry A. Wallace

(**) Term: 14 Years

(57) **CLAIM**

(21) Appl. No.: 29/124,562

I claim the ornamental design for measuring cups, as shown and described.

(22) Filed: Jun. 7, 2000

(51) LOC (7) Cl. 10-04

FIG. 1 is a perspective view in a nested position.

(52) U.S. Cl. D10/46.3

FIG. 2 is a top view in a nested position.
FIG. 3 is a cross-sectional view in a nested position along the centerline 3—3 of FIG. 1.

(58) **Field of Search** D10/46.2, 46.3;
D7/691, 692; 73/426, 429; 294/55

FIG. 4 is a side elevation view in a nested position from one side, the view from the opposite side being identical.

(56) **References Cited**

FIG. 5 is a bottom view in a nested position.

U.S. PATENT DOCUMENTS

FIG. 5 is a bottom view in a nested position; FIG. 6 is a front end view in a nested position; FIG. 7 is a rear end view in a nested position; and-
